UNITED STATES PATENT OFFICE.

JOHN S. WARD, OF CHICAGO, ILLINOIS, ASSIGNOR TO PHENIX LUBRICATOR COMPANY, OF CHICAGO, ILLINOIS, A CORPORATION OF ILLINOIS.

LUBRICATING-PUMP.

No. 893,118.

Specification of Letters Patent.

Patented July 14, 1908.

Application filed March 9, 1908. Serial No. 419,913.

To all whom it may concern:

Be it known that I, JOHN S. WARD, a citizen of the United States, residing at Chicago, in the county of Cook and State of Illinois, have invented a certain new and useful Improvement in Lubricating-Pumps, of which the following is a specification.

My invention relates to pumps, especially lubricating pumps, and the object is to improve certain characteristics of the pump shown and described in my application filed December 23, 1907, Serial No. 407,846. Specifically, the improvements in the present application result from first, the providing of a plunger within the hollow piston adapted to work within the tube which is located within said piston, and second, the locating of the inlet valve which supplies liquid to the piston chamber, directly beneath said piston chamber instead of at the side thereof, as in the previous application.

In the accompanying drawings which illustrate the improved construction, Figure 1 is a side elevation of the casing which contains the inner working parts; Fig. 2 is a vertical section thereof taken on the line 2—2 of Fig. 3, Fig. 3 is a horizontal section taken on the line 3—3 of Fig. 1, Fig. 4 is a horizontal section taken on the line 4—4 of Fig. 2. Fig. 5 is a vertical section taken on the broken line 5—5 of Fig. 3.

In the drawings, the valve casing 10 has a horizontal piston chamber 11. A tube 12 is arranged in the casing in such manner as to lie mostly within said piston chamber and communicates with the pump chamber 13. Said tube is rigidly fastened to the casing by means of the screw 12^a (Fig. 3) or in any other suitable manner, and has an outside diameter less than the diameter of said piston chamber. Said tube is located concentrically within the piston chamber so as to leave a cylindrical space for receiving the hollow reciprocating piston 30, hereinafter described. The chamber 13 has an inlet port 14 provided with an inlet valve 15 and an outlet port 16 provided with an outlet valve 17. Communicating with the piston chamber 11 is an inlet port 18 provided with an inlet valve 19. Said port and valve are located directly beneath said piston chamber instead of at the side thereof as shown in the previously mentioned application, the advantage in the present construction being that the flow of liquid is straight through

the valve and there are no lateral forces or side currents tending to unseat the valve or produce leakage past it. Above said piston chamber is located an outlet port 20 provided with a valve 21. The piston chamber 11 extends to a point at or slightly beyond the parts 18 and 20 but has no communication through the casing with the chamber 13. The pipe 22 leads from the outlet port 20 and is intended to convey the oil or other liquid to the machine bearings or other destination.

In the casing below the valve 19 is a screw cap 23, and if this cap is removed, the piston chamber may be supplied with liquid directly from the outside of the casing through the port 18 and valve 19. In the preferred form of device, however, instead of being supplied directly from the outside, the liquid is led to it from the pump chamber 13 through pipe 24 to a sight feed 25, thence through pipe 26 to the passage 27, which communicates with the inlet port 18. By thus leading the liquid from one pump chamber to another the liquid makes a continuous passage through them and the pump becomes what may be termed a "tandem" pump, wherein force is applied to the liquid at two different points in its passage.

The piston 30 is hollow so as to fit over the tube 12 and is closed at its outer end by the head 31, as best shown in Fig. 2. A plunger 32 is rigidly secured inside the piston and is so constructed as to make a close sliding fit within the tube 12. Said plunger in its preferred form is long enough to reach nearly to the inner end of said tube when the piston is at the inner extremity of its travel. The object in providing plunger 32 is to reduce the amount of space communicating with the chamber 13; and also to decrease the liability of leakage between the outside and inside of tube 12, for it is obvious that when plunger 32 is absent, the liquid gains access to the inside of the piston behind tube 12, and under high pressure there would be some possibility of leakage between the outside of said tube and the inside of the piston. With the plunger present, however, the liquid cannot gain access to the inside of tube 12 except for a limited distance. In consequence, leakage from one pump chamber directly to the other through tube 12 is practically impossible, no matter how high pressure the pump is working against.

Any suitable means may be employed for

causing the travel of the piston, but description is unnecessary here as such operating means form no part of the present invention and are well known in the art.

5 Having thus described my invention, what I claim as new and desire to secure by Letters Patent, is:

1. A pump having a casing provided with a piston chamber and ports leading thereto and therefrom, an inlet and an outlet valve for said ports, said inlet valve being located directly beneath its port, a hollow piston fitting in said piston chamber and being closed at its outer end, and a tube in said casing, open at both ends, and adapted to fit within said piston, said casing having a second pair of ports and valves therein and said tube communicating at one end with said second pair of ports and valves.

20 2. A pump having a casing provided with a piston chamber and ports leading thereto and therefrom, an inlet and an outlet valve for said ports, the inlet valve being located directly beneath its port, a hollow piston fitting in said piston chamber and being closed at its outer end, a tube rigidly fastened in said casing and being open at both ends, one end of said tube lying within said piston and being closed thereby, a passage for ingress and egress of liquid to and from the end of the tube opposite to the end which is closed by said piston.

3. In a pump, the combination of a casing having a piston chamber and so constructed that liquid may enter and leave said chamber through said casing, an inlet valve located directly beneath said piston chamber and guarding the entrance thereto, an outlet valve located above said piston chamber and guarding the exit therefrom, a tube in said casing, said casing having a chamber communicating with the inside of said tube whereby liquid may enter and leave said casing without entering said piston chamber, and a piston fitting in said piston chamber for causing liquid to enter and leave it, said piston being hollow and closed at one end and fitting over said tube for causing liquid to enter and leave the chamber communicating with said tube.

4. A pump having a casing provided with a pump chamber and suitable valves therefor, a tube communicating with said pump chamber, a closed-end piston fitting over said tube, said piston chamber and pump chamber being separated from each other by a portion of the casing, suitable valves for

said piston chamber, and a plunger fastened to said piston and fitting in said tube.

5. A pump having a casing provided with a pump chamber and suitable valves therefor, a tube communicating with said pump chamber, a closed-end piston fitting over said tube, said piston chamber and pump chamber being separated from each other by a portion of the casing, suitable valves for said piston chamber, a plunger fastened to said piston and fitting in said tube, and a duct leading from one of said chambers to the other whereby the liquid may be acted upon at two points in its travel through the casing.

6. A pump having a casing provided with a piston chamber and a pump chamber and suitable valves therefor, a tube communicating with said pump chamber, a closed-end piston fitting over said tube, said piston chamber and pump chamber being separated from each other by a portion of the casing, suitable valves for said piston chamber, a plunger fastened to said piston and fitting in said tube, and a duct leading from said pump chamber to said piston chamber.

7. In a pump, a casing, a tube mounted therein, an inlet and an outlet port provided with valves communicating with one end of said tube, a hollow piston fitting over said tube, a piston chamber separated from the above mentioned ports and valves, said piston chamber being adapted to receive said piston, an inlet port located directly beneath said piston chamber, a check valve therefor, an outlet port also communicating with said piston chamber and a check valve therefor.

8. In a pump, a casing, a tube mounted therein, an inlet and an outlet port provided with valves communicating with one end of said tube, a hollow piston fitting over said tube, a piston chamber separated from the above mentioned ports and valves, said piston chamber being adapted, to receive said piston, an inlet port located directly beneath said piston chamber, a check valve therefor, an outlet port also communicating with said piston chamber, a check valve therefor and a plunger fastened to said piston and adapted to work within said tube.

In witness whereof, I have hereunto subscribed my name in the presence of two witnesses.

JOHN S. WARD.
